UNITED STATES PATENT OFFICE.

JAMES F. REILLY, OF PHILADELPHIA, PENNSYLVANIA.

TROLLEY.

Application filed December 6, 1921. Serial No. 520,269.

To all whom it may concern:

Be it known that I, JAMES F. REILLY, a citizen of the United States, residing at Philadelphia, in the county of Philadelphia and State of Pennsylvania, have invented 5 certain new and useful Improvements in Trolleys, of which the following is a specification.

The object of my invention is to provide 10 an improved form of trolley or carriage, and parts coacting therewith, arranged to travel on an overhead cable or trackway and adapted to be operated by a simple type of power unit, which power unit may be of the stationary type, such as steam or electric unit, or which power unit may be arranged to travel with the carriage; in any event the apparatus will be simple and efficient in its 15 operation, will afford a maximum of safety for the persons engaged in and about the work, and may be quickly and efficiently operated, being to a large extent automatic in its action and adapted to be controlled, if desired; entirely by a single operator located at the power unit, or alternatively, to be partially controlled by additional operators located at the loading and discharge points of the engineering or other operation in connection with which the apparatus is used. 20

With the foregoing object in view, my invention contemplates the provision of an improved form of trolley or carriage adapted to be supported from and travel on a cable or on a trackway such as the lower flange 25 of an I beam, which may in turn be supported in any suitable manner. My invention further contemplates the provision, in connection with the above mentioned carriage, of a pulley block through which the elevating cable passes, and the further provision 30 of means adapted to automatically engage and support the pulley block in its elevated position; while the bucket carried thereby is being transported by the trolley or carriage along the cable or trackway, the pulley block being provided with lugs or supporting ledges. 35

My present invention also contemplates 40 the provision, in connection with the above mentioned trolley or carriage, of means whereby the pulley block may, if desired, be

automatically released upon certain manipulation of the cables which are provided for elevating the pulley block and for transporting the same with the bucket carried thereby. 55 My present invention also contemplates the provision of means for manually operating the means for releasing the pulley block from the carriage, and further contemplates an improved form of the arrangement of the 60 various parts of the trolley or carriage and pulley block.

The nature and characteristic features of my present invention will be more readily understood from the following description, 65 taken in connection with the accompanying drawings forming part hereof, in which—

Figure 1 is a side elevation of a trolley or carriage embodying the main features of my present invention, with the coacting pulley block shown suspended therefrom, said pulley block having operatively attached thereto a common type of grab bucket for transporting the materials, and the trolley or carriage being arranged to travel 70 on an overhead cableway; 75

Fig. 2 is an end elevation thereof;

Fig. 3 is a vertical central section thereof, taken approximately on the line 3—3 of Fig. 2; 80

Fig. 4 is a vertical section thereof, taken approximately on the line 4—4 of Fig. 3;

Fig. 5 is a side elevation, similar to Fig. 1, of a modified form of a trolley or carriage, the same being provided with a hook 85 for attaching buckets or other similar devices thereto, for transporting the materials, and being arranged to travel on an overhead trackway such as the lower flange of an I beam which may be supported in any 90 suitable manner;

Fig. 6 is an end elevation of the apparatus shown in Fig. 5;

Fig. 7 is a side elevation of another modified form of trolley or carriage having 95 mounted therein a power unit for transporting the carriage along the overhead trackway, and for elevating the pulley block; and

Fig. 8 is an end elevation of the apparatus 100 shown in Fig. 7.

Referring now more particularly to Figs.

1 to 4 of the drawings, in the particular embodiment of my invention therein shown the trolley or carriage comprises a framework 10 made up of suitable structural shapes and plates, said framework being provided with bearing blocks 11 in the upper portion thereof, which bearing blocks form a means of support for shafts 12 upon which sheaves 13 are journaled. The sheaves 13 form a means for supporting the trolley or carriage upon a suitable cable 14, which is supported at its ends beyond the points between which the material is to be transported. To any suitable portion of the framework 10 there is attached, as at 16, one end of a cable 17, which cable 17 thence extends downward and then around a pulley 18 of a pulley block 19, thence passing upward and around a sheave 20 which is journaled on a shaft 21, which shaft 21 is in turn supported by means of blocks 22 supported in any suitable manner in the framework 10 of the trolley or carriage. After passing around the sheave 20, the cable 17 extends to, and is adapted to be wound upon a controllable drum of the power unit, not shown. There is also attached to the framework 10 of the trolley or carriage the end of an additional cable 23, which also extends to, and is adapted to be wound upon another controllable drum of the above mentioned power unit, not shown, the cable 23 being provided whereby, in conjunction with the hoisting cable 17, the trolley or carriage may be shifted upon the cable 14, as will hereinafter be more fully described.

The pulley block 19 comprises side plates 25, having secured on the outer faces thereof horizontally arranged bars or steps 26, and these bars or steps 26 which are mounted on the side plates 25 of the pulley block constitute a means for seating the pulley block 19 within the trolley or carriage while the same is being transported along the cable 14. A shaft 27 is supported in the side plates 25 and in the bars or steps 26, and forms a means for journaling the sheave pulley 18 around which the cable 17 passes for the purpose of supporting said pulley block in the lower loop of said cable. Between the side plates 25 there is mounted a casting 28, arranged below the pulley 18, for properly spacing the side plates with respect to each other, and also for preventing the hoisting cable 17 from leaving the groove of the pulley 18. The side plates 25 are also continued downward and in the lower corners thereof there are mounted bolts 29, forming a means for direct attachment of the arms 30 of the grab bucket 81 without the use of hook or connecting links, as has formerly been customary. The particular construction of the grab bucket 81 need not be further described, as the same may be of any of

the common types of such devices, which are well known to those skilled in this art.

An additional cable 43 is suitably attached to the proper operative part of the grab bucket 81 for the purpose of actuating the same and passes upward around and over sheaves 44 and 45, which are suitably journaled in the framework 10 of the trolley or carriage. The cable 43 thence extends to, and is adapted to be wound upon a controllable drum of the hereinbefore mentioned power unit, not shown.

At the lower end of the trolley or carriage, on each side thereof, there is pivotally mounted a bar or pawl 31, the ends of which are journaled, by means of shaft-like ends 32, in the framework 10, and these bars or pawls 31 normally rest upon and are supported by bars or supporting ledges 33 which extend across, and are fixedly secured to the bottom portions of the respective side members of the framework 10 of the trolley or carriage. The shaft-like extensions 32, preferably at one end of each bar or pawl 31, have mounted thereon a lever arm 34, which lever arms are connected at their outer ends by means of a connecting rod 35, whereby the bars or pawls 31 are constrained to be raised and lowered in unison in their pivotal movement.

The bars or pawls 31 which are pivotally supported by means of the shaft-like extensions 32, are so positioned and arranged as to be adapted to be encountered and raised out of their normal positions by means of the bars or projecting steps 26 which are mounted on the side plates of the pulley block 19, and thereafter the same are permitted to drop to their normal positions by gravity to form a seat upon which the under edges of the bars or projecting steps 26 are adapted to normally rest after the cable has been slackened off permitting the pulley block 19 to lower by gravity to said position.

Suitably journaled in the framework 10 of the trolley or carriage is a shaft 36 which carries a projecting lever member 37, which is arranged in the path of upward movement of the pulley block 19, and is adapted to be encountered and actuated thereby when the pulley block is raised to a predetermined position within the trolley or carriage. The shaft 36 is also provided with a lever 38 which is connected, by means of a connecting rod 39, with a lever 40 which is carried by one of the pivotally mounted bars or pawls 31. Each of the supporting bars or pawls 31 is also provided with a centrally located tripping member 41, normally depending downward, but adapted, when the bars or pawls

31 are in their elevated positions, to be encountered by the bars or supporting steps 26 of the pulley block 19, as the same passes downward out of the trolley or carriage. The trolley or carriage is also provided with a fixed member 42, so located therein as to provide a means for limiting the upward movement of the pulley block 19 within the trolley or carriage. 70 is a semaphore or signal arm secured to one bar or pawl 31 whereby the operator or operators can more readily perceive the angular position of the bars or pawls 31 at all times, and particularly during the 15 operation of raising or releasing the pulley block 19.

Arranged within the trolley or carriage and suitably supported by the framework 10 thereof are vertically extending bars 20 46 which are so located as to guide and position the pulley block 19 within the trolley or carriage when the same is being manipulated with respect thereto.

The operation of the form or embodiment of my invention above described may now be explained. Assuming that the trolley or carriage is in a position directly over the material to be transported to some other point to which the cable 14 extends, 25 and the grab bucket has been lowered and actuated to fill the same with the material, the cable 23 is now held taut, through proper manipulation of the winding drums by the operator at the power unit, and the 30 cable 17 is then wound upon its drum to cause the pulley block 19 to be thereby elevated until the supporting bars or steps 26 of the pulley block 19 encounter the bars or pawls 31 of the trolley or carriage and cause the same to be raised a sufficient distance to permit the pulley 35 block to pass above the same, after which the bars or pawls 31 will fall by gravity to their normal positions, resting upon the 40 bars or supporting ledges 33 which are secured at the lower end of the framework 10 of the trolley or carriage. Either of the cables 23 or 17 may now be slackened off, whereupon the bars or supporting steps 45 50 55 60 65 70 75 80 85 90 95 100 105 110 115 120 125 130 135 140 145 150 155 160 165 170 175 180 185 - of an I beam 55, constituting a trackway which may be supported by any type of suitable framework, not shown. Also, in this form or embodiment of the invention, the 5 pulley block, instead of directly supporting the grab bucket or container, may have attached thereto a suitable hook, the means of attachment comprising the links 57 and 58, and the link 57 being supported in the pulley block 19 by means of a bolt 59. Consequently, the cable 43 for actuating the grab bucket may, in this form, be omitted, as may also the sheaves 44 and 45 for guiding said cable through the trolley or carriage. 10 Also there is shown, in connection with this form or embodiment of the invention, a lever 60 mounted on the shaft 36, which carries the releasing member 37, said lever extending outward beyond the sides of the 15 trolley or carriage and having a rope 61 suspended from its free end, whereby the bars or pawls 31 may be arbitrarily actuated by an operator located at either or both of the points of loading and discharge of the 20 buckets which are adapted to be engaged by the hook 56. By this arrangement, the pulley block 19 may be arbitrarily released from its support within the trolley or carriage, and the same be permitted to descend, 25 this arrangement being more particularly desirable in such cases when the operator at the power unit may not, owing to distance or obstructions, have a clear view of the trolley or carriage, and may thereby be prevented from actuating the cable 17 with sufficient nicety to always effect the automatic release of the pulley block 19 from within the trolley or carriage when it is desired to permit the said pulley block to descend. It will, of course, be understood, 30 however, that the lever 60 may, if desired, be used in connection with the form or embodiment of the invention shown in Figs. 1 to 4. 35 Except as above noted, the construction, arrangement and operation of the form or embodiment of my invention shown in Figs. 5 and 6 are substantially like the form or embodiment thereof shown in Figs. 1 to 4 of the drawings.
- In the form or embodiment of the invention shown in Figs. 7 and 8 of the drawings, the trolley or carriage is likewise adapted to travel and be transported on a trackway 55 such as the lower flange 54 of an I beam 55. In this instance, however, the framework 10 of the trolley or carriage is provided with a self-contained power unit 65 for the purpose of transporting the trolley or carriage 60 along the trackway and also for elevating the pulley block 19. This power unit 65 may be of any preferred type, and the detailed construction thereof forms no part of the present application. As there shown, 65 the same comprises an electric motor 66 sup-

plied with electric power in any preferred manner, not shown, and adapted to actuate, under the control of the operator, a winding drum 67 around which the hoisting cable 17 is adapted to be wound, the other 70 end of said hoisting cable being connected, as at 16, to any suitable part of the apparatus. The trolley or carriage with the power unit carried thereby, is suspended from the trackway along which the 75 same is adapted to travel by means of traction wheels 68 which are journaled from stud shafts 69 which, in turn, are supported by the framework 71 to which the upper part of the power unit 65 is secured by bolts 80 72. The traction wheels 68 are provided with flanges 73 provided with gear teeth for the purpose of driving the same by any preferred form of intermediate driving mechanism, not shown, but as will be readily 85 understood, which may be actuated by the motor 66.

In other respects the construction, arrangement and operation of the form or embodiment of the invention shown in Figs. 90 7 and 8 of the drawings are substantially like the form or embodiment thereof shown in Figs. 5 and 6 of the drawings.

It will be seen that there is thus provided a simple and efficient trolley apparatus 95 adapted to travel upon an overhead cable or trackway, for handling the materials in and about engineering operations and the like, in which apparatus the load will be positively held while the same is being transported, 100 thus affording a maximum of safety for the persons employed in and about the work, the arrangement being such that the pulley block will be positively supported within the trolley or carriage while being transported, and will be positively held therein notwithstanding the cable should break or be slackened off while the load is being transported. Furthermore, 105 the apparatus may be operated by means of a simple type of power unit, which may be so manipulated as to perform all of the elevating, transporting and releasing operations, whereby the same may, if desired, be entirely controlled by a single operator located at the power unit, or if desired, the releasing operation may be supplemented by additional operators suitably located at the proper positions with respect to the engineering work in connection with which 115 the apparatus is used.

Having thus described the nature and characteristic features of my invention, what I claim as new and desire to secure by Letters Patent is:

1. In apparatus of the character described a carriage suspended from and adapted to travel upon an overhead trackway, a controllable cable one end of which is attached to said carriage, said cable ex- 130

tending downward in a loop from said carriage, a pulley block suspended in said loop of said cable, members mounted in the carriage and adapted to be moved aside by said pulley block and to then return to their normal positions to form a seat for supporting said pulley block in said carriage, means adapted to be encountered and operated by said pulley block when the same passes to a predetermined position in the carriage for moving said supporting members to positions whereby the pulley block may be permitted to pass below the same, and means actuated by the pulley block as the same descends to return said supporting members to their normal operative positions.

4. In apparatus of the character described a carriage suspended from and adapted to travel upon an overhead trackway, a controllable cable one end of which is attached to said carriage, said cable extending downward in a loop from said carriage, a pulley block suspended in said loop of said cable, bars pivotally mounted in the carriage and adapted to be raised by said pulley block and to then return to their normal positions to form a seat for supporting said pulley block in said carriage, members movably mounted in said carriage arranged above said supporting bars and adapted to be encountered and operated by said pulley block when the same passes to a predetermined position in the carriage, link work connected with said members for moving said supporting bars to positions whereby the pulley block may be permitted to pass below the same, and means actuated by the pulley block as the same descends to return said supporting bars to their normal operative positions.

return said supporting members to their normal operative positions.

7. In apparatus of the character described a carriage suspended from and adapted to travel upon an overhead trackway, a controllable cable one end of which is attached to said carriage, said cable extending downward in a loop from said carriage, a pulley block suspended in said loop of said cable, members mounted in the carriage and adapted to be moved aside by said pulley block and to then return to their normal positions to form a seat for supporting said pulley block in said carriage, means adapted to be encountered and operated by said pulley block when the same passes to a predetermined position in the carriage for moving said supporting members to positions whereby the pulley block may be permitted to pass below the same, means actuated by the pulley block as the same descends to return said supporting members to their normal operative positions, and means adapted to position said pulley block within said carriage.

8. In apparatus of the character described a carriage suspended from and adapted to travel upon an overhead trackway, a controllable cable one end of which is attached to said carriage, said cable extending downward in a loop from said carriage, a pulley block suspended in said loop of said cable, members mounted in the carriage and adapted to be moved aside by said pulley block and to then return to their normal positions to form a seat for supporting said pulley block in said carriage, a member movably mounted in said carriage arranged above said supporting members and adapted to be encountered and operated by said pulley block when the same passes to a predetermined position in the carriage, means operatively connected with said member for moving said supporting members to positions whereby the pulley block may be permitted to pass below the same, means actuated by the pulley block as the same descends to return said supporting members to their normal operative positions, and means adapted to position the pulley block within said carriage.

9. In apparatus of the character described a carriage suspended from and adapted to travel upon an overhead trackway, a controllable cable one end of which is attached to said carriage, said cable extending downward in a loop from said carriage, a pulley block suspended in said loop of said cable, members mounted in the carriage and adapted to be moved aside by said pulley block and to then return to their normal positions to form a seat for supporting said pulley block in said carriage, a member movably mounted in said carriage arranged above said supporting members and adapt-

ed to be encountered and operated by said pulley block when the same passes to a predetermined position in the carriage, link work connected with said members for moving said supporting members to positions whereby the pulley block may be permitted to pass below the same, means actuated by the pulley block as the same descends to return said supporting members to their normal operative positions, and means adapted to position said pulley block within said carriage.

10. In apparatus of the character described a carriage suspended from and adapted to travel upon an overhead trackway, a controllable cable one end of which is attached to said carriage, said cable extending downward in a loop from said carriage, a pulley block suspended in said loop of said cable, bars pivotally mounted in the carriage and adapted to be raised by said pulley block and to then return to their normal positions to form a seat for supporting said pulley block in said carriage, a member movably mounted in said carriage arranged above said supporting bars and adapted to be encountered and operated by said pulley block when the same passes to the uppermost position in the carriage, link work connected with said member for moving said supporting bars to positions whereby the pulley block may be permitted to pass below the same; a manually operable lever connected therewith for arbitrarily actuating said supporting bars and means actuated by the pulley block as the same descends to return said supporting bars to their normal operative positions.

11. In apparatus of the character described a carriage suspended from and adapted to travel upon an overhead trackway, a pair of controllable cables the ends of which are attached to said carriage, one of said cables extending downward in a loop from said carriage, a pulley block suspended in said loop of said cable, bars mounted on the sides of said pulley block, members mounted in the carriage and adapted to be moved aside by said bars on the sides of said pulley block and to then return to their normal positions to form a seat for supporting said pulley block in said carriage, means adapted to be encountered and operated by said pulley block when the same passes to a predetermined position in the carriage for moving said supporting members to positions whereby the pulley block may be permitted to pass below the same, and means actuated by the bars on the sides of the pulley block as the same descends to return said supporting members to their normal operative positions.

12. In apparatus of the character described a carriage suspended from and adapted to travel upon an overhead track-

- way, a pair of controllable cables the ends of which are attached to said carriage, one of said cables extending downward in a loop from said carriage, a pulley block suspended in said loop of said cable, bars mounted on the sides of said pulley block, members mounted in the carriage and adapted to be moved aside by said bars on the sides of said pulley block and to then return to their normal positions to form a seat for supporting said pulley block in said carriage, a member movably mounted in said carriage arranged above said supporting members and adapted to be encountered and operated by said pulley block when the same passes to a predetermined position in the carriage, link work connected with said member for moving said supporting bars to positions whereby the pulley block may be permitted to pass below the same, a manually operable lever operatively connected therewith for arbitrarily actuating said supporting bars, and means actuated by the pulley block as the same descends to return said supporting bars to their normal operative positions.

13. In apparatus of the character described a carriage suspended from and adapted to travel upon an overhead track-way, a pair of controllable cables the ends of which are attached to said carriage, one of said cables extending downward in a loop from said carriage, a pulley block suspended in said loop of said cable, bars mounted on the sides of said pulley block, members mounted in the carriage and adapted to be moved aside by said bars on the sides of said pulley block and to then return to their normal positions to form a seat for supporting said pulley block in said carriage, a member movably mounted in said carriage arranged above said supporting members and adapted to be encountered and operated by said pulley block when the same passes to a predetermined position in the carriage, link work connected with said member for moving said supporting bars to positions whereby the pulley block may be permitted to pass below the same, a manually operable lever operatively connected therewith for arbitrarily actuating said supporting bars, and tripping members operatively connected with said supporting bars adapted to be encountered by the pulley block as the same descends to thereby return said supporting bars to their normal operative positions.

14. In apparatus of the character described a carriage suspended from and adapted to travel upon an overhead track-way, a pair of controllable cables the ends of which are attached to said carriage, one of said cables extending downward in a loop from said carriage, a pulley block suspended in said loop of said cable, projecting members mounted on the sides of said pulley block, bars pivotally mounted in the carriage and adapted to be raised by said projecting members on the sides of said pulley block and to then return to their normal positions to form a seat for supporting said pulley block in said carriage, a member moy-

ably mounted in said carriage arranged above said supporting bars and adapted to be encountered and operated by said pulley block when the same passes to a predetermined position in the carriage, link work connected with said member for moving said supporting bars to positions whereby the pulley block may be permitted to pass below the same, a manually operable lever operatively connected therewith for arbitrarily actuating said supporting bars, and means actuated by the pulley block as the same descends to return said supporting bars to their normal operative positions.

15. In apparatus of the character described a carriage suspended from and adapted to travel upon an overhead track-way, a pair of controllable cables the ends of which are attached to said carriage, one of said cables extending downward in a loop from said carriage, a pulley block suspended in said loop of said cable, projecting members mounted on the sides of said pulley block, bars pivotally mounted in the carriage and adapted to be raised by said projecting members on the sides of said pulley block and to then return to their normal positions to form a seat for supporting said pulley block in said carriage, a member movably mounted in said carriage arranged above said supporting bars and adapted to be encountered and operated by said pulley block when the same passes to a predetermined position in the carriage, link work connected with said member for moving said supporting bars to positions whereby the pulley block may be permitted to pass below the same, a manually operable lever operatively connected therewith for arbitrarily actuating said supporting bars, and means actuated by the pulley block as the same descends to return said supporting bars to their normal operative positions.

16. In apparatus of the character described a carriage suspended from and adapted to travel upon an overhead track-way, a pair of controllable cables the ends of which are attached to said carriage, one of said cables extending downward in a loop from said carriage, a pulley block suspended in said loop of said cable, said pulley block having bars mounted on and extending from the sides thereof, bars pivotally mounted in the carriage and adapted to be raised by said bars on the sides of said pulley block and to then return to their normal positions to form a seat for supporting said pulley block in said carriage, a member movably mounted in said carriage arranged above said supporting bars and adapted to be encountered and operated by said pulley block when the same passes to a predetermined position in the carriage, link work connected with said member for moving said supporting bars to positions whereby the pulley block may be permitted to pass below the same, a manually operable lever operatively connected therewith for arbitrarily actuating said supporting bars, and means actuated by the pulley block as the same descends to return said supporting bars to their normal operative positions.

member for moving said supporting bars to positions whereby the pulley block may be permitted to pass below the same, a manually operable lever operatively connected therewith for arbitrarily actuating said supporting bars, tripping members operatively connected with said supporting bars adapted to be encountered by the pulley block as

the same descends to thereby return said supporting bars to their normal operative 10 positions, and means mounted in said carriage for positioning the pulley block therein.

In testimony whereof I have hereunto signed my name.

JAMES F. REILLY
